CLAIM

The ornamental design for a drinking straw, as shown and described.

DESCRIPTION

FIG. 1 is a top, front, right side perspective view of a drinking straw showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged cross-sectional view taken along line 8-8 in FIG. 4;

FIG. 9 is a top, front, right side perspective view thereof with a plurality of small edible articles therein;

FIG. 10 is an enlarged view of FIG. 2; and,

FIG. 11 is an enlarged view of FIG. 3.

The dashed broken lines in the drawing depict portions of the drinking straw that form no part of the claimed design. The dashed broken lines of the edible articles in FIG. 9 depict environment that forms no part of the claimed design.
